UNITED STATES PATENT OFFICE.

MAURICE GALIBERT, OF NEW YORK, N. Y.

LABELING-MACHINE.

1,344,081.

Specification of Letters Patent. Patented June 22, 1920.

Application filed January 17, 1919, Serial No. 271,557. Renewed December 17, 1919. Serial No. 345,584.

To all whom it may concern:

Be it known that I, MAURICE GALIBERT, a citizen of the United States, residing in the city, county, and State of New York, have 5 invented certain new and useful Improvements in Labeling-Machines, of which the following is a specification.

This invention relates to labeling and wrapping machines; its object being to produce a machine for use in labeling or wrapping cylindrical containers, such containers as now shown having one or both ends enlarged by end caps.

I use the term gum herein as applicable 15 to any suitable kind of adhesive, and by labels I of course include wrappers.

In the accompanying drawings forming part hereof and illustrating the principle of this invention in the best mode now known 20 to me of applying that principle,

Figure 1 is a side elevation of one form of machine embodying the present invention, and shows in elevation its principal driving mechanism.

25 Fig. 2 is a top plan view of what is shown in Fig. 1, some parts being omitted for greater clearness.

Fig. 3 is a side elevation of gumming mechanism, partially in vertical elevation at 30 line 3—3 of Fig. 1.

Fig. 4 is a view which is a partial end elevation of what is shown in Fig. 3, but shows the feed rolls in transverse section at a line corresponding to line 4—4 of Fig. 2.

35 Fig. 5 is a horizontal vertical section of the hopper at line 5—5 of Fig. 1.

Figs. 6 and 7 are details of the adjustable hopper sides, Fig. 6 being partially in section at a line corresponding to line 6—6 of 40 Fig. 5, and Fig. 7 being a vertical elevation.

Fig. 8 is a cross-sectional elevation of the label-applying mechanism at line 8—8 of Fig. 1.

Fig. 9 is a perspective detail of a portion 45 of the label-carrying drum with a gummed label in place between the periphery of the drum and label-supporting belts, and also shows guide pulleys for the belts.

Fig. 10 is an enlarged side elevational 50 detail of the machine showing particularly a portion of the hopper-gate controlling mechanism with all indicated containers above the gate, and

55 Figs. 11 and 12 are views similar to Fig. 10. In Fig. 11 the bottom container of the pile held by the hopper is in its initial

wrapping position, and in Fig. 12 the container has passed into and is being wrapped by the endless wiper belt of the container labeling mechanism in coöperation with the 60 periphery of the drum.

All three views, Figs. 10, 11 and 12, illustrate portions of the container labeling mechanism.

Fig. 13 is a top plan view and 65

Fig. 14 is a side elevational view of the driving mechanism shown in Fig. 1 for actuation of the intermittent feed rolls, hopper-gate controlling mechanism, and drum.

Fig. 15 is an elevational view of a seg- 70 mental gear and coöoperating spur gear by which intermittent feeding motion is given to the label feed rolls, Fig. 15 being partially in section at line 15—15 of Fig. 14 and looking in the direction of the arrows 75 shown in Fig. 14.

Fig. 16 is an elevational view partially in section at line 16—16 of Fig. 14 and looking in the direction of the arrows shown in Fig. 14, and illustrates the controlling cam 80 for opening and closing the hopper gate.

Fig. 17 is an elevational view of a partially labeled or wrapped container each end of which has its circumferential dimension increased by the flange of an end cap. 85

Fig. 18 is an elevational detail of the feed roll and gumming roll attachment, and shows particularly the driving means for an end of one of the feed rolls.

Fig. 19 is an elevational detail showing 90 a means of adjustably mounting a label-supporting belt pulley on its shaft.

Fig. 20 is a rear elevational view of the back plate of the hopper and of pulleys carried on a shaft supported thereby, and 95 also of dependent label-engaging fingers secured thereby, and

Fig. 21 is a perspective view of one of said fingers detached.

In the drawings, the two upstanding side 100 frames comprise front corner posts 1 and rear corner posts 2, a front and a rear corner post at each side being connected between their ends by an integral horizontal under web 3 having an upper horizontal web 3^a. The side frames are spaced laterally apart to accommodate between them a revoluble label-supporting drum of large diameter for simultaneously carrying a plurality of labels in endwise position one to 110 another. Each front corner post has at convenient height for the operator, a for-

wardly-extending horizontal-bracket 4; and above the bracket 4 an upwardly and forwardly extending bracket 5 provided with an outside downwardly and forwardly slanting flange 6. The brackets 4 and 5 and the flanges 6 of one side frame are laterally opposed to the corresponding parts of the other side frame. The brackets 4 support feeding and gumming mechanisms. 10 The brackets 5 support a label-applying and labeled - container - discharging mechanism, forwardly of a vertical hopper for the containers to be labeled. Each flange 6 has bolted to it at 7 the lengthwise-extending bottom flange 8 of a detachable side frame 9 of the label-applying and labeled-container-discharging mechanism, and each side frame 9 has at each end an upwardly and forwardly projecting arm, the lower 20 and forward arm being indicated by 10 and the upper and rearward arm by 11, these arms being laterally opposed in pairs to support a pair of transverse upper rolls for an endless wiper belt 12 of the label-applying and labeled-container-discharging mechanism. Each back post near but above its foot has a rearwardly-projecting bracket 13, one opposed to the other; and at its upper end bends outwardly and upwardly at 30 14, such bent portion on one side being opposite the corresponding bent portion on the other side. The horizontal webs 3 support journal-boxes for the ends of a transverse horizontal drum-shaft 15 carrying a somewhat narrow label-supporting drum 16 a little wider than the longest containers to be labeled, but of large diameter for reception on its periphery of a plurality of end-wise located labels or wrappers L each for 40 application on the periphery of a container. The peripheral wall of the drum is shown with opposed inturned flanges at right-angles to it, and is preferably made of thin metal. Its periphery is coated with hard 45 rubber 17 as a foundation for a sponge rubber coating 18, which affords a resilient surface for the ungummed faces of the labels or wrappers L which being of paper have their opposed margins tempered by an adhesive in parallel marginal strips l; the back of the label being supplied with a thicker-bodied adhesive in a strip l', the edges of which are parallel to but spaced apart from the opposed edges of the tempered marginal 50 strips l thus forming parallel gumless strips l² on the gummed surface of the label for cleanly coöperation with the endless label supporting belts 19 the inner runs of which partially or arcuately inclose the drum periphery, leaving a gap at the front side of the machine between the under and upper terminal pulleys between which the inner runs of the belts travel in contact with the 55 gumless strips l² on the sponge rubber coating of the drum; the outward runs of the

belts being spaced away from each inner run.

Drum shaft 15 has at one end a spur gear 20 in mesh with a spur gear 21 on a transverse counter shaft 22 journaled at its ends 70 in journal boxes supported by the horizontal webs 3, the counter shaft being provided with a pulley 23 from which a belt 24 runs to a pulley 25 on the shaft 26 of a motor 27. Thus the drum is continuously rotated, with 75 its upper front periphery descending.

The bottom end flanges 26^a of the upstanding lateral sides 27 of the hopper are adjustably clamped opposite one another to the rear end walls of the brackets 9 by lag-screws 28 through transversely elongated slots 29 in the flanges whereby the two opposed lateral side walls of the hopper are adjustable from and toward each other for reception of containers of different lengths 80 and the ends of which are in sliding contact with the lateral walls 27 when they are set in an adjusted position for reception of a pile of containers of uniform length. 85

The back wall of the hopper is bounded 90 by a fixed, transverse, upstanding plate 30 to the back side of which are fixed a pair of rearwardly and downwardly extending arms 31 in the free opposed ends of which are bearings for a transverse shaft 32 spaced 95 apart from and above the drum. Between the arms this shaft is provided with a pair of grooved endless-belt-supporting pulleys 33 spaced laterally apart along the length of the shaft. A pair of endless parallel label-supporting belts 19 the inward runs of 100 which partially inclose the periphery of the drum as stated are provided for coöperation with the drum periphery for carrying successive gummed labels under the hopper 105 and to label-applying and labeled-container-discharging mechanism forward of the hopper for progressive rolling application to the peripheries of containers dropped successively from the hopper and successively subjected to the action of the label-applying mechanism which together with the hopper is positioned over an upper front peripheral portion of the drum oppositely to a gap between forward upper and under terminal 110 pulleys for the endless belts; label-supports and label feed rolls and gumming roll being located at the gap. 115

The upper outward runs of these endless belts travel rearward from the pulleys 33 120 each over a rear upper, grooved pulley 34 on a transverse shaft 35 journaled in the ends of the bent portions of the rear posts; thence downwardly over grooved pulleys 36 on a transverse back bottom shaft 37 journaled in the ends of the back post brackets 13, back of and adjacent which each belt loops downward by reason of a weight 38 suspended by a weight carrying a grooved pulley 39 that is hung in the bight of each 125 130

loop in each belt; the weights tensioning the belts and keeping their inner runs taut over the belt-embraced portions of the drum between the terminal pulleys. From the pulleys 39, the outer runs of the belts travel forwardly under the drum to and upwardly over grooved pulleys 40 on a transverse shaft 41 journaled above and adjacent the feet of the front posts 1 to and over pulleys 10 42 on a transverse gumming roll shaft 43 (Fig. 3), the pulleys 42 being the under front terminals of the belts.

The pulleys 42 and their shaft 43 are members of the gumming mechanism; the 15 inward belt runs pass over and rearwardly of and downwardly from the pulleys 42 in contact with labels on the drum periphery and travel with the drum in clockwise direction (Fig. 1) to, under and upwardly from 20 upper terminal pulleys 44 on a transverse shaft 45 journaled in rearwardly-projecting ears 46 carried by the back plate 30 of the hopper; and thence over the first-mentioned pulleys 33.

25 For greater certainty in keeping the inner runs of the endless belts parallel and under proper tension for coöperation with the revoluble drum as a gummed label-carrying mechanism, three sets of three flanged 30 pulleys each for the inner runs of the label-supporting belts, are shown, spaced apart between the terminal pulleys. One set is located between the front posts adjacent the under forward periphery of the drum; another set is located between the back posts adjacent the back under periphery of the drum; and another set is located between the back posts adjacent the upper rearward periphery of the drum. Each set comprises a 35 40 pair of transverse idler shafts 47 spaced laterally apart and having their ends journaled in opposite frame posts, and a third transverse idler shaft 48 having its ends also journaled in such posts. The three 45 shafts of each set are so located one to another that their axes would lie at the apices of an equilateral triangle if it were laid out from such axes, the two shafts 47 being nearer the drum periphery than the shaft 48. Each of these shafts 47 carries two 50 flanged pulleys 49 spaced apart along the length of the shaft and the shaft 48 carries two correspondingly disposed flanged pulleys 49; the three pulleys provided for the 55 inner run of each belt being in edgewise alignment with all the other belt-supporting pulleys and each of which is laterally adjustable on its shaft for lateral adjustment of the belts to suit labels of different widths 60 for containers of different lengths.

In Fig. 19, I show a shaft which may be considered as any one of the pulley shafts with two laterally adjustable pulleys on it, each pulley representing any of the pulleys 65 carried by the shaft and each pulley having

through its body a screw-hole for reception of a set-screw 50 by which the pulley when moved along the shaft for lateral adjustment is fixed in its adjusted position by impingement of the screw on the shaft.

The upstanding back plate 30 of the hopper is rigidly connected to upper webs 3* by rearwardly and downwardly extending arms 51. The two lateral sides 27 of the hoppers as already stated are laterally adjustable 75 and their rear edges are in slidable contact with the front of the back plate 30. The front margins of the lateral sides 27 of the hopper are opposingly provided each with a horizontally elongated slot 52. For the 80 front side 53 of the hopper a number of plates of varying widths are provided, to suit the lengths of the containers in the hopper pile and formed with outwardly-projecting laterally-opposed holed ears 54 85 through which clamp bolts 55 are passed into the slots 52 to hold the front wall of the hopper in an adjusted position relatively to the back-plate according to diametric dimensions of the containers in the pile. 90

Thus the hopper is adjustable as well as the belt-supporting pulleys and label-supporting belts for containers of different lengths, the hopper being also adjustable for containers of differing diameters; and all of 95 the hopper except its back plate may be readily removed for installation if desired of a different style or kind of hopper.

In order that the transverse label-applying mechanism carried on the flanges 6 may 100 be also removed for installation of a different style or kind of label-applying mechanism, the side frames 9 are demountably secured in place by the bolts 7.

The machine thus far described is a label-ing machine of which machine the novel and salient feature is a label carrier comprising the endless label-supporting belts co-operating with the revoluble drum for simultaneously supporting a plurality of 105 successive gummed labels, each gummed label being in course of travel from the gumming apparatus to the hopper for a sufficient length of time to permit moisture in the thinner gum, which in practice is 110 kept heated, for the margins of the labels, to temper the margins so that they will be stretchable on container ends of larger diameter than the intermediate body portion of the containers. To this end the drum is 115 desirably some five or six feet in diameter in order to support a series of successive labels in course of marginal tempering while one is being wrapped around the container; and the label-carrying drum and 120 endless belt features described may be incorporated in machines having other kinds of hoppers, label-applying, gumming and feeding apparatus than herein shown, if so 125 desired. 130

The horizontal brackets 4 support a pair of horizontal parallel L-shaped label-supporting guides 56 of known kind; and also support a transverse, thick-bodied gum trough 57 in the ends of which the ends of the shaft 58 of a gum-supply roll 59 are mounted, an end of the shaft projecting and being provided with a spur gear 60 which meshes with a spur gear 61 on the upper and parallel gumming roll shaft 43, the gumming roll being indicated by 62. The ends of its shaft 43 are journaled respectively in the outer upstanding end wall of each of two tempering gum containers 63 each of which is shown clamped at 64 to an end wall flange 65 of the intermediate thick-bodied gum trough 57.

The label-gumming roll 62 is supplied with the thicker-bodied gum by the under roll 59 turning in the contents of the trough.

The belt pulleys 42 are each narrowly spaced apart from an opposed end of the gumming roll 62 and rotate between such roll end and the inward upstanding side 65 of an end gum reservoir 63, the shaft 43 passing through both upstanding sides of each reservoir 63 and being provided with a marginal lateral gumming roll 66 which turns in a reservoir 63. The gumming rolls 62 and 66, 66 and the gum-supply roll 59 being spur-geared together, turn synchronously and are driven by the label-supporting belts 19 tensioned in the grooved pulleys 42 on the shaft 43 of the gumming rolls. The purpose of the intermediate gumming roll 62 is to apply the thicker-bodied gum to the label back midway between its edges; that of the end gumming rolls 66 is to apply a thinner gum of a quality to effect tempering of each margin of the label, the marginal strips l , l of gum on the label back being severally spaced apart from the intermediate and usually wider strip l' of gum on the label back, and each marginal gum strip being separated from the intermediate gummed strip by an ungummed strip l^2 in contact with a belt 19.

The labels, in the present form of machine, are initially fed printed side up and back down between a pair of transverse feed rolls 67 on shafts 68. The under feed roll shaft 68 has a bevel gear 69 which meshes with a bevel gear 70 on the end of a horizontal shaft 71 carried in an upstanding bearing 72 supported by one of the brackets 4; the rearward end of shaft 71 having a spur gear 72 in mesh with a mutilated spur gear 73 for intermittent feeding movements of the feed rolls and fixed on the front end of a horizontal shaft 74 which is supported between its ends in a projecting bracket-bearing 75 on a front post. Rearward of its bearing 75, this shaft 74 has a spur gear 76 and terminates in a bevel

gear 77 which meshes with a bevel gear 78 on the drum shaft 15 whereby rotation of the drum shaft drives the feed rolls but intermittently because of the mutilated spur gear 73, to feed a label toward the drum, the advancing end of the label impinging by its back side on the gummed surfaces of the gumming rolls 62 and 66, 66; and the belts 19 which are under the back side of the label acting initially as separators to lift the advancing end of the label from the gumming rolls and transfer it into position on the drum between the inner runs of the belts and the elastic periphery of the drum. Thus a succession of gummed labels are carried toward the under end of the hopper and thence toward the gap between the terminal pulleys of the endless belts 19 to the label-applying mechanism. The feed-roll shafts 68 are spur-geared together at 85 68^3 to receive their synchronous rotation.

It is desirable that the thicker-bodied gum supplied to the label back by the gumming roll 62 should be evenly and thinly distributed on that roll, and hence the gum-supply roll 59 is provided for it; but for the tempering of the margins of the label, a thinner gum having more moisture is supplied to the label margins by the gumming rolls 66 for thoroughly wetting the margins and making them laterally stretchable in their compressive rolling application to the container ends. On the shaft 80 rearwardly of its bearing 81 there is mounted a cam wheel 82 having eight cam lugs 83. As shown this cam wheel is integral with a hub 84 which carries another cam-toothed wheel 85 having ten cam lugs. The ten-lugged cam wheel is used when there are ten labels on the drum; and the eight-lugged cam wheel when there are eight labels on the drum. The shorter the labels the more of them can be carried by the drum; and cam wheels having any desired number of cam lugs each corresponding to a label may be used. As shown, the hub 84 is feathered to the shaft 80 by a groove 86 and held in adjusted position by a set-screw 87 through the hub into the groove. The eight-lugged cam wheel is shown in operative position and the ten-lugged one in inoperative position. The cam lugs 83 are spaced at equal distances apart around the periphery of the wheel, and successively engage a cam roll 88 on the under end of a vertical, upwardly-extending pawl rod 89 which between its ends is endwise slidable in a frame bracket 90. Its upper end is loosely connected to an outwardly-projecting horizontal pin 91 fixed to a pawl 92, the rear end of which is pivoted on an end of the shaft 32. The forward end of the pawl has a downwardly pointing finger 93 for engagement successively with any one of the two diametrically opposite teeth 94 of a ratchet wheel 95 mounted on an end of a 130

transverse gate-carrying shaft 96 which is journaled in bearings 97 at the opposite lateral margins of a gate-opening 98 in the back plate 30 of the hopper. The gate shaft 5 has a pair of diametrically-opposed lengthwise-extending plates each forming a gate 99, the two gates being alternately revoluble through said opening 98 into and out of the hopper chamber for release of the bottom container and for supporting the pile by means of one of the gates under the pile. When the pawl is lifted from the ratchet wheel 95, the weight of the containers or last container, there being a weight on 10 the pile, on the underlying gate causes the gate shaft to rotate, bringing the diametrically opposed gate 99 in under the next successive container above the released container; and the pawl rod then descending 15 either by its own weight or preferably by reason of the expansion of a coiled spring 100 against the tension of which it is lifted by a cam tooth 83, causes the pawl finger to come into the path of the next succeeding 20 ratchet wheel tooth 94. The coiled spring is mounted between a collar 101 on the rod and a projecting lug 102 on the upper web 3^a, the rod passing through a hole in the lug. The cam lugs 83 have their cam-actuating peripheries of such extent as to keep 25 the cam-rod lifted for proper intervals of time and it is when the cam-roll on the foot of the rod rides off the cam-actuating peripheries of the cam lugs that the spring 30 causes the rod to descend with its cam roll then between the cam lugs on the periphery 35 of the cam wheel.

The dropping container to be labeled initially contacts with the advancing gummed 40 end of the advancing label rearwardly of the label-applying apparatus which comprises a transverse endless wiper belt 12 carried by belt rolls 104, one between the arms 10 and the other between the arms 11 45 of the side frames 9. Each wiper belt roll is carried by a transverse shaft 105 the ends of each of which are journaled in adjustable journal-boxes 106 with which the inner ends of journal-box adjusting screws 107 50 are pivotally connected in a known way, the journal-boxes being movable in elongated slots 108 in the arms 10 and 11, and threaded through the outer end walls of the slots all as common in many machines. The under 55 run of the wiper belt is opposed to the upper forward periphery of the drum, forwardly of the hopper and at the gap between the upper and under terminal pulleys of the belts 19 which are round in cross-section. The under run of the wiper belt is 60 also spaced apart from said peripheral portion of the drum to which it is opposed by a space corresponding to the diameter of the container; and the under run of the wiper belt travels in the direction of the descend-

ing travel of said peripheral portion of the drum but at a slower speed in order that the under run of the wiper belt may cause the container C being labeled to rotate in the counter-clockwise directions (Fig. 12) while 70 the drum is rotating in the clockwise direction, whereby the container will be rolled on the remainder or succeeding rear portion of the gummed label; while at the same time it is being bodily conveyed by the clockwise rotation of the drum downwardly and forwardly past the under front end of the wiper belt into a position of discharge below this label-applying and labeled-container-discharging mechanism and above the 75 feeding and pasting mechanisms. In its bodily travel under the wiper belt, the container with the label on it may turn several times on its own axis; and the bodily travel is permitted because of the positive action of 80 the drum periphery on the labeled container against the upwardly yielding movement of the under run of the wiper belt between its end rolls, and in part also by a kind of progressive seating of the under periphery 85 of the labeled container on the yielding sponge rubber peripheral coating of the drum. This yielding coating also permits the progressive seating and consequent molding of the tempered and laterally 90 stretchable margins of the paper labels over the inner edge walls c of the container end cap flanges c' as well as over such flanges, while the intermediate gummed strip l' of the label is being snugly wrapped around 95 the body of the container between the edge walls c. Thus a more perfectly labeled tubular container is obtained than has been heretofore obtainable except by careful manual 100 wrapping of the labels in place; and at a 105 much more rapid rate of production. The wiper belt is given its described direction of travel by means of a side drive belt 109 (Fig 2) from a belt wheel 110 on the drum shaft to and over a belt wheel 111 on one 110 of the wiper belt roll shafts 105, thereby driving the upper run of the wiper belt downwardly and forwardly. Each side frame 9 of the label-applying apparatus is provided with a lengthwise-extending light 115 leaf spring 112 the ends of each of which are fixed at 112^a (Fig. 8) to the dependent arms 113 of right-angle bracket, the upper horizontal arm of which has an elongated slot 114 through which a clamp bolt 115 passes from a horizontal lug 116 of a side plate 9 to effect a slight endwise adjustment 120 of the container at equal distances from the edges of the under run of the wiper belt. The back plate 30 is provided with a pair 125 of dependent fingers the under end bends of which are indicated by 117, each of which has an under bent end 118 the convex side of which is slightly above the label on the drum to act as a downhold for the advanc- 130

ing end of the label. These two fingers are laterally adjustable on a cross-rod 119 on which they are loose. They hang down with their under ends slightly above the labels 5 and are severally bent at 120 to avoid the label-supporting belts 19 so that their under ends may contact with the gumless portions l^2 of the label. In order to drive the under run of the wiper belt at a speed less than the 10 rotational speed of the drum periphery, the wiper belt rolls 104 are of smaller diameter than the pulley 110 (Fig. 2) from which the rolls 104 are driven by the belt 109, the pulley 110 being on the drum shaft 15. In 15 practice, the diameters of pulleys 110 and 111, and of the wiper belt rolls 104 are proportioned to give about one foot surface travel of the wiper belt to about three feet surface travel of the drum.

20 When conoidal containers are to be labeled, all of the hopper except its back plate and the label-applying mechanism are removed; and other kinds of hopper and label-applying mechanism substituted if so desired.

25 For any given mutilated feed-roll drive gear 73, another differently-timed mutilated gear may be substituted; and for any given cam wheel 85 another differently-timed cam wheel may be substituted; whereby while the 30 drum, endless label-supporting belts, gumming rolls, and wiper belt are traveling at constant speed, the movements of the intermittent feed rolls and of the hopper gate 35 actuating mechanism may be timed as required for different lengths of labels.

While I have described a container having two end caps the flanges of which give to the end portion of the container a diameter 40 exceeding the diameter of the intermediate portion of the container, and have accordingly shown a label with two gumless lengthwise-extending belt-engaged portions l^2 , and yet some tubular containers have 45 only one flanged end cap and in such cases only one gumless portion l^2 is requisite and only one belt 19 and only one separate gum reservoir 63 and gum roll 66.

The machine may be used for other purposes than particularly mentioned, and various changes may be made in its construction without departure from my invention.

What I claim is,—

1. The combination in a labeling machine, 55 of a revoluble drum; an endless label-supporting belt having an inner run partially inclosing the periphery of the drum; belt-supporting means comprising terminal members for the end turns of the belt, such 60 terminal members being spaced apart one from the other to form a gap opposed to the drum between the terminal members, one of which is opposed to a portion of the drum periphery which is between the drum 65 sides and spaced inwardly of a peripheral

edge of the drum leaving a peripheral margin of the drum uncovered by the belt at each side of the belt; and a label-gumming apparatus constructed to deliver a gummed label with its gummed surface outward at 70 one terminal end of the belt between the inner run of the belt and the periphery of the drum, the label-gumming apparatus comprising a gum container and a gum roll alined with said peripheral margin of the 75 drum, and also comprising an independent gum container and gum roll alined with that portion of the gummed periphery which is at the other side of the belt; and label supplying mechanism; the label-applying mechanism coöperating with the label-supporting belt and drum to apply a 80 label on a rotating container and to discharge the labeled container.

2. The combination in a labeling machine 85 of a revoluble drum; a plurality of endless label-supporting belts each having an inner run partially inclosing the periphery of the drum and being spaced laterally apart on the drum periphery and between the drum 90 sides, leaving the peripheral margins of the drum uncovered by the belts, and leaving the periphery of the drum between the belts uncovered; belt-supporting means comprising terminal members for the end turns of 95 the belt, such terminal members being spaced apart from the other to form a gap opposed to the drum periphery and spaced apart laterally to support the belts as described; and a label-gumming apparatus 100 constructed to deliver a gummed label with its gum surface outward between the inner run of the belts and the periphery of the drum, such label gumming apparatus comprising in alinement with each uncovered portion of the drum periphery at each side of each belt, an independent gum container and gumming means; and label-applying mechanism; the label-applying mechanism 105 coöperating with the label-supporting belts 110 and drum to apply a label on a rotating container and to discharge the labeled container.

3. In the combination of claim 1, a container hopper, a hopper gate, automatic gate 115 opening and closing mechanism, the label-applying mechanism coöperating with the label-supporting belts and drum to apply a label on a rotating container and to discharge the labeled container.

4. In the structure of claim 2, a container hopper, a hopper gate, automatic gate-opening and closing mechanism, the label-applying mechanism coöperating with the label-supporting belts and drum to apply a 125 label on a rotating container and to discharge the labeled container.

5. The combination of a stationary container hopper; a hopper gate and automatic gate opening and closing mechanism; 130

- a label-applying mechanism; and an intermittent label-feed mechanism; a revoluble drum; an endless label-supporting belt having an inner run partially inclosing the periphery of the drum; and a label-gumming means; the drum, belt, and label-gumming means being continuously operable; and the intermittent feeding mechanism and automatic gate opening and closing mechanism 10 each comprising timing members whereby their operations are timable.
6. The combination of a continuously rotating drum; an endless label-supporting belt having an inner run partially inclosing the periphery of the drum; belt-supporting means comprising terminal members for the end turns of the belt, such terminal members being spaced apart one from the other to form a gap, and the terminal 15 members together with the drum, supporting the belt between the drum sides; and a label-gumming means comprising a plurality of independent gum containers and gumming rolls; a container hopper; a hopper gate and automatic gate opening and closing mechanism; and a label-applying mechanism, the label-applying mechanism comprising an endless wiper belt having an inner run opposed to the drum periphery 20 and traveling in a direction the reverse of the direction of travel of that portion of the drum periphery to which the inner run of the wiper belt is opposed.
7. In the combination of claim 6, a freely elastic waterproof peripheral coating on the drum.
8. The combination of a continuously rotating drum; an endless label-supporting belt having an inner run partially inclosing the periphery of the drum; belt-supporting means comprising terminal members for the end turns of the belt, such terminal members being spaced apart one from the other to form a gap, and the terminal 25 members together with the drum supporting the belt between the drum sides; and a label-gumming means comprising a plurality of independent gum containers and gumming rolls; a container hopper; a hopper gate and automatic gate opening and closing mechanism; and a label-applying mechanism, the label-applying mechanism comprising an endless wiper belt having an inner run opposed to the drum periphery and traveling in a direction the reverse of the direction of travel of that portion of the drum periphery to which the inner run of the wiper belt is opposed; and springs for holding the container in endwise relation to the width of the inner run of the wiper belt.
9. The combination of a continuously rotating drum; an endless label-supporting belt having an inner run partially inclosing the periphery of the drum; belt-supporting
- means comprising terminal members for the end turns of the belt, such terminal members being spaced apart one from the other to form a gap, and the terminal members together with the drum supporting the belt 70 between the drum sides; and a label-gumming means comprising a plurality of independent gum containers and gumming rolls; a container hopper; a hopper gate and automatic gate opening and closing mechanism; and a label-applying mechanism, the label-applying mechanism comprising an endless wiper belt having an inner run opposed to the drum periphery and traveling in a direction the reverse of the direction of travel of that portion of the drum periphery to which the inner run of the wiper belt is opposed; two adjacent gum reservoirs; a terminal pulley for a label-supporting belt; and a gumming roll in each reservoir; the 75 gumming rolls and terminal pulley having a common shaft.
10. The combination in a labeling machine, of a revoluble drum; an endless label-supporting belt having an inner run partially inclosing the periphery of the drum; belt-supporting means comprising terminal members for the end turns of the belt, such terminal members being spaced apart one from the other to form a gap opposed to the drum between the terminal members, one of which is opposed to a portion of the drum periphery which is between the drum sides and spaced inwardly of a peripheral edge of the drum leaving a peripheral margin of the drum uncovered by the belt at each side of the belt; and a label-gumming apparatus constructed to deliver a gummed label with its gummed surface outward at one terminal end of the belt between the inner run of the belt and the periphery of the drum, the label-gumming apparatus comprising a gum container and a gum roll alined with said peripheral margin of the drum, and also comprising an independent 100 gum container and gum roll alined with that portion of the gummed periphery which is at the other side of the belt; a label-downhold finger directed toward but spaced apart from the path of the label being carried on the periphery of the drum; and label-applying mechanism.
11. The combination in a labeling machine, of a revoluble drum; an endless label-supporting belt having an inner run 105 partially inclosing the periphery of the drum; belt-supporting means comprising terminal members for the end turns of the belt, such terminal members being spaced apart one from the other to form a gap opposed to the drum between the terminal members, one of which is opposed to a portion of the drum periphery which is between the drum sides and spaced inwardly of a peripheral edge of the drum leaving a pe- 110

peripheral margin of the drum uncovered by the belt at each side of the belt; and a label-gumming apparatus constructed to deliver a gummed label with its gummed surface outward at one terminal end of the belt between the inner run of the belt and the periphery of the drum, the label-gumming apparatus comprising a gum container and a gum roll alined with said peripheral margin of the drum, and also comprising an independent gum container and gum roll alined with that portion of the gummed periphery which is at the other side of the belt; and tensioning means for the label-supporting belt; and label-applying mechanism.

12. The combination in a labeling machine, of a revolute drum; an endless label-supporting belt having an inner run partially inclosing the periphery of the drum; belt-supporting means comprising terminal members for the end turns of the belt, such terminal members being spaced apart one from the other to form a gap opposed to the drum between the terminal members, one of which is opposed to a portion of the drum periphery which is between the drum sides and spaced inwardly of a peripheral edge of the drum leaving a peripheral margin of the drum uncovered by the belt at each side of the belt; a label-gumming apparatus constructed to deliver a gummed label with its gummed surface outward at one terminal end of the belt between the inner run of the belt and the periphery of the drum, the label-gumming apparatus comprising a gum container and a gum roll alined with said peripheral margin of the drum, and also comprising an independent gum container and gum roll alined with that portion of the gummed periphery which is at the other side of the belt; a hopper having adjustable lateral sides and an intermediate side adjustable relatively to an opposed intermediate side; and adjustable pulleys for the label-supporting belt; the hopper having a discharge opening located to permit engagement of a container with a label at a place adjacent the initially operative end of the label-applying mechanism.

13. The combination of a revolute drum; pulleys for a pair of endless label-supporting belts the inner runs of which partially inclose the periphery of the drum; a gumming mechanism comprising three alined gum reservoirs; three gumming rolls; a shaft by which the gumming rolls are carried, two of the belt-supporting pulleys being also carried by said shaft; a label-feeding mechanism; and a label-applying mechanism; and means for moving containers to be labeled into the path of labels on the drum periphery; the label-feeding mechanism operating to feed labels successively between the belts and the drum periphery, the gumming rolls operating to apply to the

label backs three strips of gum the intermediate gum strip of which is spaced apart from the other strips, the drum and pulleys carrying each label-supporting belt in contact with an ungummed portion of the label back and also carrying the labels between the drum periphery and said means for moving containers to be labeled into the path of labels on the drum periphery.

14. In the combination of claim 13, said means for moving containers to be labeled into the path of labels on the drum periphery comprising a hopper and hopper gate, hopper gate controlling mechanism, and mechanism for operating label-feeding mechanism intermittently.

15. In the combination of claim 13, the label-applying mechanism comprising an endless wiper belt the under run of which is opposed to the drum periphery, the drum periphery being elastic; and means for driving the under run of the wiper belt in a direction the reverse of that of the drum.

16. In the combination of claim 13, a hopper; both the hopper and the label-applying mechanisms being demountable.

17. In the combination of claim 13, a container hopper and a hopper gate both of which are demountable.

18. In the combination of claim 1, the label-applying mechanism comprising a wiper belt having an inner run opposed to and spaced apart from the periphery of the drum for reception of a container therebetween, the wiper belt operating to wipe the pasted labels on the container and to discharge the labeled container.

19. In the combination of claim 1, the label-applying mechanism comprising a wiper belt having an inner run opposed to and spaced apart from the periphery of the drum for reception of a container therebetween, the wiper belt operating to wipe the pasted labels on the container and to discharge the labeled container; and opposed devices for lengthwise positioning a container relatively to the edges of the inner run of the wiper belt.

20. The combination of a revolute label-supporting drum; an endless label-carrying belt; gumming mechanism; a hopper; a hopper gate; a mechanism for actuating the hopper gate intermittently; intermittently revolute feed rolls for labels; mechanism for intermittently rotating the feed rolls; a label-applying mechanism comprising a wiper belt and wiper belt rolls; means for driving the wiper belt at a speed less than the peripheral speed of the drum with the under run of the wiper belt opposed to the periphery of the drum.

21. The combination of a revolute label-supporting drum; an endless label-carrying belt; gumming mechanism; a hopper; a hopper gate; a mechanism for actuating the

hopper gate intermittently; intermittently revoluble feed rolls for labels; mechanism for intermittently rotating the feed rolls; a label-applying mechanism comprising a wiper belt and wiper belt rolls; means for driving the wiper belt at a speed less than the peripheral speed of the drum with the under run of the wiper belt opposed to the periphery of the drum; and means for continuously rotating the label-supporting drum.

22. The combination with a revoluble label-supporting drum; an endless, arcuate label-supporting belt partially inclosing the drum; and terminal belt pulleys for the end turns of the belt, the terminal belt pulleys

being spaced apart to form a gap between the end turns of the belts; of a gumming mechanism comprising a plurality of independent gum reservoirs each alined with a portion of the drum periphery at a side of the belt for obtainment of separated parallel strips of gum on the label; and label-applying mechanism; the label-applying mechanism coöperating with the label-supporting belt and drum to apply a label on a rotating container and to discharge the labeled container. 20 25

In testimony whereof I have hereunto set my hand this 9th day of January, 1919.

MAURICE GALIBERT.
